CLAIM

The ornamental design for a jogbox hand grip, as shown and described.

DESCRIPTION

FIG. 1 is a top front right side perspective view of the jogbox hand grip;

FIG. 2 is a right side elevational view, the left side being a mirror image thereof;

FIG. 3 is a top plan view;

FIG. 4 is a bottom plan view;

FIG. 5 is a front elevational view;

FIG. 6 is a rear elevational view; and,

FIG. 7 is a cross-sectional view taken along line 7—7 of FIG. 3.

In the drawings, the dashed lines are for illustrative purposes only, and form no part of the claimed design.

CERTIFICATE OF CORRECTION

PATENT NO. : Des. 599,687 S
APPLICATION NO. : 29/323026
DATED : September 8, 2009
INVENTOR(S) : Mark Thomsen

Page 1 of 1

It is certified that error appears in the above-identified patent and that said Letters Patent is hereby corrected as shown below:

On the Title Pg., in the Item (Description), change “FIG. 7 is a cross-sectional view taken along line 7-7 of Fig. 3” to --FIG. 7 is a bottom rear right side perspective view.--

Signed and Sealed this

Twenty-fourth Day of November, 2009

David J. Kappos
Director of the United States Patent and Trademark Office
